FIG. 1.

FIG. 3.

FIG. 2.

Inventor

B. Marsh

By

R. A. Tracy, Attorney.

UNITED STATES PATENT OFFICE.

BERT MARSH, OF TWIN FALLS, IDAHO.

CHECK-HOLDER.

1,243,326.

Specification of Letters Patent. Patented Oct. 16, 1917.

Application filed October 23, 1916. Serial No. 127,230.

To all whom it may concern:

Be it known that I, BERT MARSH, a citizen of the United States, residing at Twin Falls, in the county of Twin Falls and State 5 of Idaho, have invented certain new and useful Improvements in Check-Holders, of which the following is a specification.

For the convenience of their customers, merchants in small towns and rural districts 10 usually have on hand a number of blank checks from the different banks in their town or locality but annoyance and inconvenience is caused and much time is frequently lost in trying to find a blank check 15 on a particular bank when one is needed as the checks are liable to become misplaced or distributed among other papers in the merchant's office. The present invention, therefore aims to provide for the use of 20 such merchants, a device adapted to securely hold in position for convenient use, a number of check pads, the device being so constructed that it may be left lying upon the counter or hung in any convenient place 25 so that a customer desiring to present a check in payment for merchandise may, in the use of the device, select a blank check on the particular bank in which he deposits his money and is not required to request a 30 check of the merchant nor is the merchant put to the trouble of locating a blank check on the particular bank which the customer has in mind.

It is another aim of the invention to so 35 construct the device that while the check pads will be securely held thereon, the means provided for holding them in place will not obscure any portion of the check nor will the check be mutilated in removing 40 the same from the device.

Another aim of the invention is to so construct the holding means for the check pads that the same will securely hold a pad of any ordinary thickness and in fact will hold 45 such a pad even to the last or bottom check thereof.

In the accompanying drawings,

Figure 1 is a perspective view of the device embodying the present invention, and 50 Fig. 2 is a horizontal sectional view therethrough;

Fig. 3 is a detail sectional view through one end of one of the clips.

The device embodying the present invention includes a flat base 1 which may be of 55 wood, metal, or in fact, of any material suit-

able for the purpose and of any desired size depending, of course, upon the number of check pads which are to be held thereon. Also, this base may be of any desired outline and finished in any desired manner and it is preferably provided at its upper edge with an eye 2 to permit of its being hung upon a nail or hook if desired. In that embodiment of the invention illustrated in the drawings, the device is designed to hold three check pads and for this purpose, three clips are provided upon the front face of the base 1 and are located one above another and suitably spaced. Each of these clips 60 comprises an intermediate attaching portion indicated by the numeral 3 and this portion is secured by means of rivets 4 or other suitable fastening elements to the said base 1. The clip is formed from resilient 65 metal and extending from each end of the attaching portion 3 is a clip arm indicated by the numeral 5. It will be apparent by reference to Fig. 1 that the clip arms 5 extend in opposite directions and in mutual 70 alignment and each arm is provided at its lower edge and at its outer end with a downwardly extending clip finger 6 which is preferably substantially triangular or spur shaped and relatively narrow. In order 75 that the clip arms 5 may be sprung upwardly so as to permit of the engagement of the upper edge of a check pad beneath the fingers 6, each arm is provided at its outer end with a finger knob indicated by 80 the numeral 7.

In the use of the device, a check pad to be held is disposed upon the base 1 with its upper edge extending below the lower ends of the fingers 6 and then first one and then 85 the other of the clip arms are lifted against their inherent resiliency and the said upper edge of the check pad is introduced beneath the respective fingers 6. Of course, when the finger knobs are released, the fingers 90 will firmly grip the upper edges of the check pad and the pad will be securely held in place upon the base 1. However, the fingers being relatively narrow and being 95 as stated substantially triangular or spur shaped will not obscure any portion of the face of the uppermost check nor will the check be mutilated when torn from the pad in the usual manner. Furthermore, the fingers offer minimum resistance to the removal of the uppermost check although they 100 serve to securely hold the pad in place both 105 110

before and after the removal of a check therefrom. It will be understood, of course, that before their application to the base, the 5 clips are slightly bowed throughout their length, and that, being of resilient metal, when they are secured in place, the clip arms will bear very firmly against the face of the base 1 and consequently, the clip fingers will firmly hold a single check as well 10 as a relatively thick pad of checks and consequently even the last or bottom check of a pad may be used and need not be discarded.

By reference to Fig. 3 it will be observed 15 that the clip fingers 6 are slightly curved toward their ends in the direction of the said base, so that the fingers will securely engage the face of a stack of checks and slipping of the checks will be more effectually prevented.

Having thus described the invention, what 20 is claimed as new is:

1. In a device of the class described, a base, a clip having an attaching portion secured to the base, resilient clip arms extending 25 from opposite ends of the said attaching

portion substantially in alinement with each other and having a normal tendency to bear against the face of the base, and a tapered finger projecting from one longitudinal edge of each of the clip arms substantially at the 30 end thereof, the said fingers being turned inwardly in the direction of their ends toward the said face of the base.

2. In a device of the class described, a base, a clip having an attaching portion secured to the base, resilient clip arms extending from opposite ends of the said attaching portion substantially in alinement with each other and having a normal tendency to bear 35 against the face of the base, a tapered finger projecting from one longitudinal edge of each of the clip arms substantially at the end thereof, the said fingers being turned inwardly in the direction of their ends toward the said face of the base, and a finger 40 piece upon the outer face of each clip arm adjacent the clip finger thereof.

In testimony whereof I affix my signature.

BERT MARSH. [L. s.]
